A.S. Blanchard
Design for Heating Stove
Dated Aug 26. 1843

No 8

Des. 8

Monro S. Blanchard, Albany, New York
Letters Patent No. 8 dated August 2d, 1843. —

The Schedule referred to in these Letters Patent and
making part of the same. —

Be it known that F. Monroe S. Blanchard
of the City and County of Albany in the State of New-
York have invented or produced a new design, figure,
or statue for ornamental purposes such as Radiators
for Stoves &c and I do hereby declare that the following
is a full and exact description of the same reference
being had to the accompanying drawings in which Fig.
1. exhibits the figure on a high pedestal and Fig. 2. the
same figure on a lower pedestal.

My design is an erect figure of Washington, the
hair being dressed in the peculiar fashion of his age and
quiet behind, the coat is of the fashion of the times in
which he lived and his whole person is enveloped in
a flowing mantle except the head, left breast and arm,
a part of the right hand and the toes of the boots; this
mantle is so arranged as to appear gathered up-
and wrapped around him by his right fore arm
and hand, which are placed horizontally across the
breast — the other arm hangs straight down by his
side and in that hand (the left, there is a scroll
partly unrolled, below which the drapery hangs in

in full folds and the mantle hangs down so as to touch the pedestal all round thus making the statue as large at that point as it is above or larger. This design can be used as a radiator for heating apartments or other ornamental purposes to which it is fitted - it may be placed on a high or low base to suit the taste or convenience of the purchaser.

What I claim as new and for which I desire to be secured letters patent is the above described and represented statue having the mantle and other attributes arranged as herein set forth either for the purposes of a radiator or as an ornament.
